MINNIE SHELTON SELLMAN, OF BRIDGEPORT, CONNECTICUT.

DROP-END BOX.

1,080,933.

Specification of Letters Patent.

Patented Dec. 9, 1913.

Application filed August 13, 1912. Serial No. 714,826.

To all whom it may concern:

Be it known that I, MINNIE SHELTON SELLMAN, a citizen of the United States, residing at Bridgeport, county of Fairfield, 5 State of Connecticut, have invented an Improvement in Drop-End Boxes, of which the following is a specification.

This invention has for its object to provide a simple and inexpensive drop end box, 10 the principle of which is adapted to music roll boxes, shoe boxes, corset boxes and to boxes for numerous other articles of merchandise that are kept in boxes either before or after sale by the dealer.

15 As an important application of the principle of the invention I will illustrate and describe it as a music roll box.

It is well understood that in music stores where large quantities of music rolls are on 20 sale it is necessary to pile the boxes up, frequently many rows deep, and that when any roll in the pile is wanted, except a top one, it is exceedingly inconvenient to get the box out from the pile, it being necessary to entirely withdraw boxes of the style now in 25 general use from the pile before the roll can be removed therefrom. The same difficulty occurs in homes where many rolls are frequently piled together and very often 30 numerous rolls must be taken down and the pile torn to pieces in order to get some special roll that may be desired and which ordinarily is not at the top of the pile. In order to overcome these objections and provide a box that will permit the roll to be 35 removed and replaced without withdrawing the box or disturbing the pile and which will also provide convenient means for withdrawing the box from the pile should the 40 roll or other contents be sold, I have devised the novel drop end box of which the following description in connection with the accompanying drawing is a specification, reference characters being used to indicate 45 the several parts.

Figure 1 is a perspective view of my novel box in the open position to permit the removal or replacement of a roll, the rear end of the case being broken away; Fig. 2 an 50 elevation partly in section of the outer end of the box and case in the open position; Fig. 3 a similar view of the inner end of the box and case; Fig. 4 a longitudinal section of the case and partial section of the box 55 in the closed position, and Fig. 5 is a horizontal section and Fig. 6 a vertical section

of a variant form of my novel drop end box in the open position.

10 denotes the box which is provided at its outer end with a drop end 11, the bottom of which is hinged, as at 12, to the bottom of the box. The drop end in the case of a music roll box may be two inches more or less in length and its side walls, end wall and bottom correspond with the box. 60

13 denotes the case which just receives the box and the drop end and is open at one end only.

14 denotes a tape, one end of which is attached to and extends inside the inner end 70 of the case, the other end being attached to and extending outside the inner end of the box, the objects being to limit the outward movement of the box relatively to the case after it has been drawn out of the case far 75 enough to permit the drop end to swing downward and also to enable the operator by continuing to pull upon the drop end after the tape has been extended, as in Fig. 1, to start the case also outward so that the user 80 may take hold of it conveniently and draw it out of the pile should the roll or other article belonging in the box be sold. The drop end is made long enough so that when the box is drawn out and the drop end 85 allowed to swing downward, the end of the roll will project from the box, so that it may be easily grasped by the fingers of the user, as clearly indicated in Fig. 1. The label designating the music of the roll is 90 affixed to the end wall of the drop end, which is specifically indicated by 15, so that it may be conveniently inspected at all times. The drop end is provided with a loop 95 16 which always remains outside the case in position to be grasped by the fingers of the user when it is required to draw out the drop end and remove the roll from the box or when it is required to draw out both 100 box and case either before or after the roll is removed.

The form illustrated in Figs. 5 and 6 differs in that the box has no inner end and need not necessarily extend but a short distance into the case. The function that the 105 inner end of the box performs in the other form is performed in this form by means of a flap 17 hinged to the top of the case at its inner end, as at 18, from which tapes 19 extend to the box so that when the drop 110 end and box are drawn outward, as in Figs. 5 and 6, the flap will be drawn forward also

and will bear against the inner end of the roll and force it outward far enough so that it may be easily grasped by the user. In other respects the operation is precisely the same as the operation of the other form.

Having thus described my invention I claim:

1. A drop-end box comprising a case open at one end, a box slidably mounted in said case, a drop-end independent of said case and having a hinged connection with the forward end of said slidable box, said end having a portion slidably engaging said case, said drop end being provided with means whereby the box and drop end may be withdrawn from the case, and a flexible pulling connection between the box and the rear end of the case and located wholly within the latter, whereby the case may be drawn

along with the box after the latter has been 20 partially withdrawn from said case.

2. A drop end box comprising a case open at one end, a box slidably mounted in said case, a drop end pivotally connected with said box and provided with means whereby 25 the box may be withdrawn from the case, an internal flap hinged to the case, and a flexible pulling connection between the box and said flap and located wholly within the case, whereby the case may be drawn along 30 with the box after the latter has been partially withdrawn from said case.

In testimony whereof I affix my signature in presence of two witnesses.

MINNIE SHELTON SELLMAN.
